UNITED STATES PATENT OFFICE

93,858

DESIGN FOR A WEIGHING SCALE

Mathias J. Weber and Russell E. Vanderhoff, Chicago, Ill., assignors to Continental Scale Works, Chicago, Ill., a corporation of Illinois

Application September 8, 1934, Serial No. 53,242

Term of patent 14 years

To all whom it may concern:

Be it known that we, MATHIAS J. WEBER and RUSSELL E. VANDERHOFF, citizens of the United States, residing at Chicago, Cook County, Illinois, have invented a new, original, and ornamental Design for a Weighing Scale, of which the following is a specification, reference being had to the accompanying drawing forming part thereof.

Figure 1 is a side view of a weighing scale showing our new design; and

Figure 2 is a perspective view of the same.

We claim:

The ornamental design for a weighing scale as shown.

MATHIAS J. WEBER.
RUSSELL E. VANDERHOFF.
